UNITED STATES PATENT OFFICE

WILLIAM LOWY, OF BRONX, AND JOSEPH GITLITZ, OF NEW YORK, N. Y.

DESIGN FOR A RADIOCABINET OR SIMILAR ARTICLE

Application filed April 26, 1930. Serial No. 35,407. Term of patent 3½ years.

To all whom it may concern:

Be it known that we, WILLIAM LOWY and JOSEPH GITLITZ, both citizens of the United States, and residents respectively of the Bronx, in the county of Bronx and State of New York, and of the city, county, and State of New York, have invented a new, original, and ornamental Design for Radiocabinet or Similar Article, of which the following is a specification, reference being had to the ac-

companying drawing, forming part thereof.

The figure is a perspective view of a radiocabinet or similar article.

The back of the cabinet is substantially plain and flat.

I claim:

The ornamental design for a radiocabinet or similar article, as shown and described.

WILLIAM LOWY.
JOSEPH GITLITZ.
